CONVERTIBLE TABLE AND SEAT

James R. Mayer, Atlanta, Ga.

Application March 25, 1955, Serial No. 496,844

5 Claims. (Cl. 155—43)

This invention relates to a convertible table, and it has particular reference to a table which is convertible into a bench, chair or other seat.

The invention is especially directed to a table which may be employed in rooms or other spaces, such as the cafeterias or assembly halls of schools or other organizations, and may function as a table when meals are being served but is convertible into a chair, bench or other seat when the room is to serve as an assembly hall, ballroom, theater or the like.

In accordance with present practice, a properly equipped school is provided with at least one large room which, in normal use, functions as a cafeteria or dining hall for the students but which may serve also as an assembly hall, ballroom or theater. A room of this kind is furnished with a complement of tables and chairs to properly accommodate the students at meals, and this type of furnishing is adequate and proper for cafeteria or dining hall use, but in a conversion of the room or space for use as an assembly hall, ballroom or theater the tables lose their utility and present a storage problem. Ordinarily for such conversion the tables are moved against the walls of the room, and the chairs are so disposed, either also against the walls, or in predetermined arrangement upon the floor, as to best serve the purpose for which the room is to be used.

Obviously, when the tables are not in use they occupy floor space, always at a premium, which might otherwise be serviceable, and one object of the invention is to provide a table which may be converted into a chair, bench or seat and will thus augment the seating capacity provided by the usual complement of chairs without adding to the number of pieces of furniture normally provided for the room.

Another object of the invention is to provide a convertible table the parts of which are so designed, and so function, as to make unlikely injury to children and others unskilled in their operation when conversion from table to chair form, and vice versa, is undertaken.

A further object is to provide means whereby the co-operating parts of the device may optionally be releasably retained in table-forming or seat-forming association.

Another object is to provide yielding means for normally urging the cooperating parts of the device to, and retaining them in, a position intermediate their table-forming and seat-forming positions.

A still further object is to provide a table convertible to a seat in which adequate leg room is provided beneath the table top.

Still another object is to provide a convertible table of rugged construction which may be subjected to rough handling and repeated conversion from table form to seat form, and vice versa, without injury.

In the interest of economy, and also to provide the desired ruggedness, the frame elements of the device are preferably made as sheet-metal stampings, and a further object of the invention is, therefore, to provide a design

2

which lends itself readily to fabrication from sheet metal forms.

With these and other objects in view the invention comprises a table convertible into a chair, bench or other seat, including a frame having a pair of similar, spaced, hollow, ground-supported pedestals, a pair of similar yoke members pivotally supported upon said pedestals, means forming a table top and a seat and seat back secured to said yoke members, means functioning between said pedestals and yoke members for releasably securing the yoke members and with them the table top and seat means optionally in table-forming or seat-forming position, and yieldable means reacting between at least one of said pedestals and the pivot means of its respective yoke member for normally biasing said yoke member, and with it the attached table top and seat means, to a position intermediate said table-forming and seat-forming positions, all as will be explained hereinafter more particularly and finally claimed.

20 In the accompanying drawings illustrating the invention, in the several figures of which like parts are similarly designated,

Fig. 1 is an end view of a convertible table embodying the features of the invention, in table-forming position,

25 Fig. 2 is a front view of the device as viewed from the left of Fig. 1,

Fig. 3 is a view similar to Fig. 1, but showing the parts in seat-forming position,

30 Fig. 4 is a front view of the device as viewed from the left of Fig. 3,

Fig. 5 is an enlarged sectional end elevation similar to Fig. 1, with parts of the pedestal broken away to disclose the means normally concealed within it, and showing the parts in full and broken lines in their various

35 positions,

Fig. 6 is a sectional front elevation taken on the line 6—6 of Fig. 5,

Fig. 7 is a perspective view showing the several co-operative elements of the pivotal mounting means,

40 Fig. 8 is a fragmentary side elevation of the outer arm of one of the yoke members,

Fig. 9 is a sectional elevation of one of the releasable latching members and its operating means,

45 Fig. 10 is an end view of the latching mechanism as viewed from the right of Figs. 5 and 9, and

Fig. 11 is a perspective view of one of the yoke members (the left-hand one of Figs. 2 and 4) looking at its inner face and omitting the parts of the table top and seat means normally attached thereto.

50 The pedestals 1 which provide the ground support for the table are preferably of hollow construction comprising similar side plates 2 (Figs. 5 and 6), U-shaped edge plates 3, and feet 4, all preferably formed as sheet metal stampings, for example sheet steel.

Substantially centrally of these pedestals, at the axes of curvature of the U-shaped edge plates 3, the side plates 2 are provided with pivot bearing openings 5 in which are rotatively journaled pivot bearing members 6 (Figs. 6 and 7) joined at their outwardly projecting flattened end portions

60 7 with the inner and outer legs 8 and 9 of yoke members 10 by means of complementary elongated apertures 11 preferably reinforced by similarly apertured reinforcing discs 12 and secured by washers 13 and bolts 14.

Secured to and between the inner legs 8 of the yoke members 10, as by welding, is the seating member which provides the seat 15 and back 16 of the chair or bench, and to the back 16 of this member and adjacent portions of the yoke member 10, particularly its outer leg 9, is attached the table top 17, as by flanges 18 and 19, respectively, and suitable fastening devices such as screws, bolts or the like 20 (Fig. 4).

The table top 17 may be formed as a sheet metal stamping, but it will preferably be formed of wood (such as ply wood) or of one of the now commonly used plastic slab materials such as "Formica," "Hardboard" or the like.

By this assembly of the parts it will be apparent that when the table top 17 is swung through 90° from table-forming position (Figs. 1 and 2) to seat-forming position (Figs. 3 and 4), it will pivot with the yokes 10 and bearing members 6 in the bearing openings 5 of the side plates 2 of the pedestals 1 and will cause these bearing members 6 to rotate through a similar angle.

Having reference particularly to Figs. 5 and 6, it will be seen that at least one, and preferably both, of the bearing members 6 is provided with a radially offstanding arm 21 to the outer end 22 of which is connected one end of each of a pair of similar springs 23, 23' the other ends of which are provided with anchoring means 24, 24' at the opposite edges of the pedestal 1. As shown in full lines in Fig. 5, the arm 21, which constitutes a spring tensioning and relaxing member, is disposed at an angle of 45° to a line perpendicular to the table top 17 and hence when this top is in table-forming position the spring 23 will be under tension to bias the top toward seat-forming position (shown in dotted lines) and the spring 23' will be substantially relaxed, and when the top is in seat-forming position the spring 23' will be under tension to bias the top toward table-forming position and the spring 23 will be substantially relaxed.

Intermediate the table-forming and seat-forming positions of the top the springs 23 and 23' may serve to bring the top to a position of rest (dot and dash lines, Fig. 5), from which it must be moved by the relatively slight manual pressure necessary to put tension upon one or the other of the springs 23, 23' to bring it to either table-forming or seat-forming position.

Referring particularly to Figs. 5, 6, 9 and 10, it will be seen that latch means are provided for securing the table top in either the table-forming or seat-forming position, these means comprising, in either one or both of the yoke members, a latching bolt 25 for engagement in one or the other of two 90° spaced keeper openings 26 (Fig. 6) in the edge plate 3 of the pedestal 1. The bolt 25 is pressed by a spring 27 so that it will normally seek its seat in one or the other of the keeper openings 26, and is furnished with a plate 28 engaged by an eccentric 29 which may be rotated by a turn button 30 so that the bolt may be released when desired. If both of the yokes are provided with the latch means, and this may be preferable, only one turn button 30 need be provided, but a shaft 31 (Fig. 6) will extend from one eccentric 29 to the other in order that the latch bolts may be actuated simultaneously.

From the foregoing it will be seen that the device of the invention is well adapted to supply the need for which it is designed. Moreover, as it may normally be used and operated by children it is so designed that it will not be injured by the rough handling to which it may be subjected and, conversely, will not present a source of injury to the children. As to this latter, it will be noted that although the biasing of the table top toward one or the other of its ultimate positions of use by the action of the springs 23, 23' will aid children in making the conversion from table to seat or bench, and vice versa, the counteraction of these springs which causes the table top to come to rest, in spring balance, at a mid position, as shown in dot and dash lines, Fig. 5, will prevent inadvertent too-rapid shift from one ultimate position to the other with possible pinching or crushing of the fingers or feet of the children.

Having reference particularly to Figs. 1, 3 and 5, it will be seen that the table top 17 is so related to the seat 15, pivot 6 and pedestals 1 that when it is in table-forming position there will be adequate knee or leg and foot room beneath it at both of its side (longitudinal) edges, and when it is in seat-forming position there will be space beneath the seat 15 for the heels of those seated upon it.

Also, the association and form of the pedestals 1 and yokes 10 is such that when the table top is in seat-forming position they will, in effect, provide continuous chair or bench arm surfaces (Fig. 3).

Various changes and modifications are considered to be within the principle of the invention and the scope of the following claims.

What I claim is:

1. A convertible table, including pedestal means, a table top, means pivotally mounted in said pedestal means and rotative with said table top for pivotally mounting said table top upon said pedestal means whereby the table top may be swung from horizontal to vertical position, and vice versa, seat means associated with said table top and swingable therewith as a unitary structure from non-seat-forming position where the table top is in horizontal position, to seat-forming position where the table top is in vertical position, an arm radially offstanding from said pivotal mounting means and rotatable therewith, and resilient means having ends connected respectively with said arm and pedestal means, and serving to bias said top to a position of resiliently controlled equilibrium substantially midway between its ultimate horizontal and vertical positions, said resilient means being put under tension by said arm when said table top is in either of its said ultimate positions and thus serving also to resiliently aid in adjustment of said top from its horizontal position to its vertical position and vice versa.

2. A convertible table, including pedestal means, a table top, means pivotally mounted in said pedestal means and rotative with said table top for pivotally mounting said table top upon said pedestal means whereby the table top may be swung from horizontal to vertical position, and vice versa, seat means associated with said table top and swingable therewith as a unitary structure from non-seat-forming position where the table top is in horizontal position, to seat-forming position where the table top is in vertical position, and yielding means comprising a pair of similar yieldable members each having one end connected with a tensioning and relaxing member carried by said pivotal mounting means and functioning upon rotation thereof in response to swinging of said table top and its other end anchored to said pedestal means, said yieldable members thereby serving upon pivotal movement of the table top to bias said top to a position of resiliently controlled equilibrium substantially midway between its horizontal position and its vertical position, said yielding means serving also to resiliently aid in adjustment of said table top from its horizontal position to its vertical position and vice versa.

3. A convertible table is claimed in claim 2, in which when said table top is in table-forming position one of the yieldable members of the pair of same is in tensioned condition and when the table top is in seat-forming position the other of said yieldable members is in tensioned condition, and cooperating latch means carried by at least one of said pedestals and its yoke member, respectively, are provided for securing said unitary structure of table top and seat means in one or the other of its ultimate table-forming or seat-forming positions, said securing means serving to thereby maintain one or the other of the yieldable members of said yieldable means under tension reacting upon the pedestal to assist in swinging said structure to its opposite ultimate position.

4. A convertible table, comprising a pair of relatively spaced ground-supported pedestals, each of said pedestals being provided with a yoke member pivotally mounted thereon, and a table top and a seat member extending from one of said yoke members to the other and connected thereto to provide a unitary structure swingable on said pivotal mountings from table-forming to seat-forming position, and vice versa, each of said pedestals being of hollow construction including a pair of vertical relatively spaced side plates and each of said yoke members having its legs complementary to and in juxtaposition

to the outer faces of the side plates of its respective pedestal, the pivotal mounting of each yoke member upon its respective pedestal including a pivot bearing member spanning the space between and journalled in the side plates of its said pedestal for pivotal movement, the opposite ends of said bearing members being formed for relatively non-rotative fixed connection with the respective yoke legs to impart rotation to said bearing member when the unitary structure of said table top and seat member is swung.

5. A convertible table as claimed in claim 4, in which at least one of said bearing members is provided with a radially offstanding arm, and resilient means connected with said arm and with its respective pedestal and serving normally to bias and maintain said unit structure of table top and seat member in a position of resiliently con-

trolled unstable equilibrium substantially midway of its limits of movement from table-forming to seat-forming position, and vice versa, said arm means and resilient means being housed by said pedestal in the space between its side plates and normally concealed and protected thereby.
